UNITED STATES PATENT OFFICE

WALTER WATLING, OF CHICAGO, ILLINOIS

DESIGN FOR A STEIN

Application filed March 29, 1933. Serial No. 47,625. Term of patent 7 years.

To all whom it may concern:

Be it known that I, WALTER WATLING, a citizen of the United States, residing at Chicago, in the county of Cook and State of Illinois, have invented a new, original, and ornamental Design for a Stein, of which the following is a specification, reference being had to the accompanying drawing, forming part thereof, in which—

Fig. 1 is a side elevation of the stein.

Fig. 2 is another side elevation taken from the left of Fig. 1.

Fig. 3 is a side elevation from the right of Fig. 1.

I claim:

The ornamental design for a stein as shown.

WALTER WATLING.
